CLAIM

The ornamental design for a grill lid, as shown and described.

DESCRIPTION

FIG. 1 is a front side perspective view of our grill lid;
FIG. 2 is a front elevation view thereof;
FIG. 3 is a rear elevation view thereof;
FIG. 4 is a left side elevation view thereof;
FIG. 5 is a right side elevation view thereof; and,
FIG. 6 is a top plan view thereof.
The broken line showing is for illustrative purposes only and
forms no part of the claimed design.
